BUILDING BLOCK

Harold C. Phillips, 246 Oakley Ave.,
Youngstown, Ohio 44512

Filed Mar. 15, 1967, Ser. No. 6,232

Term of patent 14 years

Int. Cl. D25—01

U.S. Cl. D18—2

FIGURE 1 is a perspective view of the building block showing one side, the top and one end thereof, and

FIGURE 2 is a perspective view showing the bottom, the side and the other end thereof. The side not shown is a mirror image of the side illustrated.

FIGURE 3 is a perspective view of a modification of the building block showing the top, one side and one end thereof, and

FIGURE 4 is a perspective view showing the bottom, the opposite side and the opposite end thereof.

I claim:

The ornamental design for a building block, as shown and described.
